FLEXIBLE POCKET RECEPACLE

Warner R. Buxton, Longmeadow, Mass.; Mabel Allen Buxton, Longmeadow, Mass., executrix of said Warner R. Buxton, deceased, assignor to Buxton, Incorporated, a corporation of Massachusetts

Application June 20, 1940, Serial No. 341,452

4 Claims. (Cl. 150—35)

This invention relates to flexible pocket receptacles of the type used to carry papers, letters, currency and the like, and has particular reference to the currency carrying capacities of the receptacle.

One object of my present invention is to combine in one receptacle certain advantages of the wallet type of receptacle in which currency is carried flat and unfolded, with certain advantages of the billfold type of receptacle in which the receptacle and the enclosed currency are folded to reduce the size of the receptacle when placed in the pocket.

A further object of the invention is to provide the user with a receptacle which will permit him to exercise a choice as to the manner in which the currency is to be carried.

Other and further objects will be made apparent in the following specification and claims.

In the accompanying drawing which illustrates one embodiment of my invention:

Fig. 1 is a plan view of a wallet according to my invention, the wallet being in open position;

Fig. 2 is a fragmentary view similar to Fig. 1 but with parts broken away to show the construction;

Fig. 3 is a section on line 3—3 of Fig. 1;

Fig. 4 is a fragmentary perspective view; and

Fig. 5 is a view similar to Fig. 1 but with the bill compartment released from the main body of the wallet.

Referring to the drawing the wallet is shown as comprising an outer wall 10 provided with a central vertical fold line 11 which divides the outer wall into portions 12 and 13 which may be folded upon each other along the fold line 11.

Portion 12 is provided with an inner wall member 14 which may be and preferably is an integral extension of outer wall portion 12, folded onto the inner face thereof. The bottom edges of the members 12 and 14 are stitched together as at 15 to provide between them a top and side opening pocket.

Outer wall member 13 may, if desired, be similarly provided with an inner wall member 16 folded over on the inner face of member 13 and stitched thereto along the bottom edge as at 17, or may be provided with any other desired wallet structure.

The bill compartment of the wallet is made as a separable element removable from the main body of the wallet, and comprises outer and inner wall members 20 and 21, respectively, connected together at their ends and one side edge to form a full length bill compartment therebe-

tween. Walls 20 and 21 may be coextensive or the outer wall 20 may extend slightly beyond the inner wall 21 at the mouth of the bill compartment as indicated at 22. Preferably the inner wall member 21 is of extensible construction and as shown comprises spaced end portions 23, which may be formed as extensions of outer wall 20, the outer end edges of portions 23 being stitched, or otherwise secured, as at 19 to the adjacent end edges of member 20. Portions 23 are provided with inwardly folded flaps 24 forming with portions 23 generally tubular members in which the end portions of an intermediate member 25 are slidably telescoped to bridge the gap between the portions 23.

The outer wall 20 and the sliding member 25 have a fold line 26 upon which one-half of the bill compartment element may be folded on the other half, when the element is separated from the wallet. It will thus be seen that the bill compartment of the wallet has the general characteristics of a bill fold, and may be constructed as such in any usual or desired manner so long as the structural relationships, later described, between it and the main body of the wallet, are preserved.

The dimensions of the bill compartment element are made such that it fits snugly into the pocket between wall members 12 and 14 of the main body of the wallet.

The dimension *a* of the inner wall 21 of the bill compartment element is substantially equal, making allowance for the thickness of the material, to the dimension *b* of inner wall member 14.

Similarly the overall dimension *c* of the bill compartment element is made equal to the inside dimension *d* of the pocket formed between walls 12 and 14, that is, the distance between the upper edge of member 14 and the line of stitching 15.

Wall member 14 is provided at that edge which is adjacent fold line 11 with a securing flap 30, creased as at 31—or otherwise hinged to the wall member 14—so as to be folded into the bill compartment between walls 20 and 21, as perhaps best shown in Figs. 2, 3 and 4, to thereby releasably secure the bill compartment to the wallet.

The dimension *e* of flap 30 at its hinged line of connection to wall 14 is substantially equal to the inside dimension *f* of the bill compartment—that is, the distance between the lines of stitches 19. This close fit of the base portion of flap 30 in the mouth of the bill compartment together with the extension of the flap a substantial distance into the compartment holds the latter securely to the main body of the wallet. The ex-

50 55

tended portion 22 of wall 20 serves to guide flap 39 into the bill compartment in the operation of fastening the bill compartment element to the main body of the wallet and also serves, when the element is in place in the wallet pocket or when it is being used separately, to guide currency into the compartment.

As will be apparent from Fig. 4, when the bill compartment element is secured to the wallet to form part thereof, as above described, there is provided a top and side opening pocket X between wall members 12 and 20, a top opening pocket Y between wall members 14 and 21, a side opening currency pocket Z between flap 39 and wall 20, and a "hidden," completely closed pocket between wall member 21 and flap 39 which is accessible only upon withdrawal of flap 39 and may be used for bills of high denomination.

Withdrawal of flap 39 releases the bill compartment from the wallet as shown in Fig. 5. The compartment when so released may be used in the manner of an ordinary billfold, and the main body of the wallet, minus its currency carrying capacities until the bill compartment is restored, continues in the interim to serve its other wallet purposes, flap 39 being folded back into the pocket existing between walls 12 and 14.

Many men prefer ordinarily to carry their currency, unfolded, in a wallet placed in an inside coat pocket. Frequently, however, these same men, when going coatless for example and desiring to have their money with them, are compelled to remove their bills from the conventional wallet and carry them rolled or folded loosely in a trouser pocket. The present invention for the first time provides a receptacle which meets such conditions whenever, wherever and as often as they arise, and in general provides a structure by which similar problems of adaptability in the construction of wallets for various purposes may be met.

What I claim is:

1. A flexible pocket receptacle comprising in combination, a main wallet body having an outer wall provided with a fold line dividing said wall into portions foldable upon each other along said line, an inner wall member secured to one of said portions to form a pocket open along its top and the side adjacent said fold line and closed at the other side and at the bottom, a pair of walls secured together to form an element having a compartment open along one side and closed along the opposite side and at at least one end, said element being nested full length in said pocket with its closed side and closed end engaged in the bight of the pocket walls at the closed side and closed end of the pocket, and a flap hinged to the edge of said inner wall member at the open side of said pocket and normally extending into said pocket and in overlapping engagement with the free edge of the adjacent wall of said element and with an end edge portion engaged in the bight of the walls of said element at the closed end of said compartment to releasably secure the latter in said pocket and restrained therein against substantial movement in any direction.

2. A flexible pocket receptacle comprising in combination, a main wallet body having an outer wall provided with a fold line dividing said wall into portions foldable upon each other along said line, an inner wall member secured to one of said portions to form a pocket opening toward

said fold line and closed at the opposite side and one end, a pair of wall members secured together to form a separable element having a full length bill compartment open along one side and closed along the opposite side and at at least one end, said element being nested full length in said pocket with its open side adjacent the open side of the pocket and with its closed side and closed end engaged in the bight of the pocket walls at the closed side and closed end of the pocket, the wall members forming said bill compartment having a fold line at right angles to the fold line of the main wallet body and about which one portion of said element may be folded upon another portion thereof when the element is separated from the main wallet body, and a flap disposed at the open side of said pocket and extending into the bill compartment of the element to releasably secure said element to the main wallet body in unfolded condition in said pocket and restrained therein by said flap against substantial movement in any direction.

3. A flexible pocket receptacle comprising in combination, a main wallet body having an outer wall provided with a fold line dividing said wall into portions foldable upon each other along said line, an inner wall member secured to one of said portions to form a pocket opening toward said fold line, a pair of wall members secured together to form a separable element having a full length bill compartment open along one side only, one of said last named wall members being extensible, said element being nested full length in said pocket with its open side adjacent the open side of the pocket, the wall members forming said bill compartment having a fold line at right angles to the fold line of the main wallet body and about which one portion of said element may be folded upon another portion thereof when the element is separated from the main wallet body, and a flap disposed at the open side of said pocket and extending into the bill compartment to releasably secure said element to the main wallet body in unfolded condition in said pocket and restrained therein by said flap against substantial movement in any direction.

4. A flexible pocket receptacle comprising in combination, a main wallet body having an outer wall provided with a fold line dividing said wall into portions foldable upon each other along said line, an inner wall member secured to one of said portions to form a pocket opening toward said fold line, wall members secured together to form a separable element having a full-length bill compartment open along one side and closed along the opposite side and at least one end, said element being nested full length in said pocket with its open side adjacent the open side of the pocket, the wall members forming said bill compartment having a fold line at right angles to the fold line of the main wallet body and about which one portion of said element may be folded upon another portion thereof when the element is separated from the main wallet body, and means disposed at the open side of said pocket to hold the edges of the adjacent walls of said pocket and element together substantially along their entire length to releasably secure said element in unfolded condition in said pocket of the main wallet body and close the opening between the so-held edges of said adjacent walls.
